[57] CLAIM

The ornamental design for a collapsible beverage container, as shown.

DESCRIPTION

FIG. 1 is a perspective view of a collapsible beverage container showing my new design, in its unfilled state;
FIG. 2 is a front elevational view;
FIG. 3 is a bottom plan view;
FIG. 4 is a top plan view;
FIG. 5 is a side elevational view, the opposite side being identical;
FIG. 6 is a perspective view, shown in its filled state;
FIG. 7 is a front elevational view of FIG. 6, the opposite side being identical;
FIG. 8 is a bottom plan view of FIG. 6;
FIG. 9 is a top plan view of FIG. 6; and
FIG. 10 is a side elevational view of FIG. 6, the opposite side being identical.
